UNITED STATES PATENT OFFICE.

ANNA K. MAY, OF PHILADELPHIA, PENNSYLVANIA.

DESIGN FOR CARPET.

SPECIFICATION forming part of Design No. 27,052, dated May 11, 1897.

Application filed April 2, 1897. Serial No. 630,480. Term of patent 31 years.

To all whom it may concern:

Be it known that I, ANNA K. MAY, a citizen of the United States, residing at the city of Philadelphia, in the county of Philadelphia and State of Pennsylvania, have invented and produced a new and original Design for a Carpet or other Fabric, of which the following is a specification, reference being had more particularly to the accompanying drawing, illustrating the same and forming part hereof.

The leading feature of my design comprises a Chinese or Japanese pattern of bars made up of little figures and intersecting each other from different directions to constitute grounds on which appear ornaments grouped to form single figures.

In the drawing, *a* is the body, *b* the border, and *a b* the complete carpet.

c are little figures which make up the bars *d*, that intersect each other in a zigzag manner, leaving grounds *f* between them.

g are ornaments made up of little figures and displayed singly on the grounds *f*.

The design of my invention will be best understood by reference to the accompanying drawing, and it may be expressed in different colors or combination of colors and applied to velvet, Wilton, Brussels, ingrain, and other carpets.

What I claim as my invention, and desire to secure by Letters Patent, is—

1. In a design for a carpet, the body *a*, substantially as shown.
2. In a design for a carpet, the border *b*, substantially as shown.
3. The design for a carpet consisting of the body *a*, and border *b*, substantially as shown.

In testimony whereof I have hereunto signed my name.

ANNA K. MAY.

In presence of—

CHAS. J. SCHAEFER,
WINFIELD S. H. KNOFF.
